US0D1040355S

(12) United States Design Patent (10) Patent No.: US D1,040,355 S
(45) Date of Patent: * Aug. 27, 2024

(54) WOUND PATCH

(71) Applicant: Huizhou Foryou Medical Devices Co., Ltd., Huizhou (CN)

(72) Inventors: Suhan Li, Huizhou (CN); Jinwen Mo, Huizhou (CN); Weiwei Chen, Huizhou (CN)

(73) Assignee: HUIZHOU FORYOU MEDICAL DEVICES CO., LTD., Huizhou (CN)

() Term: 15 Years

(21) Appl. No.: 29/779,984

(22) Filed: Apr. 22, 2021

(30) Foreign Application Priority Data

Apr. 9, 2021 (CN) 202130200250.0

CLAIM

The ornamental design for a wound patch, as shown and described.

DESCRIPTION

FIG. 1 is a front view of a wound patch according to a first embodiment of our design;

FIG. 2 is a front view of a wound patch according to a second embodiment of our design;

FIG. 3 is a front view of a wound patch according to a third embodiment of our design; and,

FIG. 4 is a front view of a wound patch according to a fourth embodiment of our design.

The oblique lines in the drawings depict high reflective surfaces.
